UNITED STATES PATENT OFFICE

JOHN BODNAR, OF ATLASBURG, PENNSYLVANIA

WIRE REEL CARRIER

Application filed April 15, 1930. Serial No. 444,584.

This invention relates to wire reels and has special reference to brakes for such reels.

One important object of the invention is to improve the general construction of wire reels.

A second important object of the invention is to provide an improved brake construction for such reels.

A third important object of the invention is to provide braking means both for the reel itself and for the wire held thereon so that the wire will not become loose on the reel.

A fourth important object of the invention is to provide novel means whereby the brake pressure on the reel and that on the wire may be simultaneously increased or released.

A fifth important object of the invention is to provide novel means for applying the brake pressures so arranged that the pressure applied to the reel itself will be greater than that applied to the wire.

With the above and other objects in view, the invention consists in general of certain novel details of construction and combinations of parts hereinafter more fully described, illustrated in the accompanying drawings and specifically claimed.

In the accompanying drawings, like characters of reference indicate like parts in the several views, and:

Figure 1 is a side elevation of the improved reel;

Figure 2 is a front elevation thereof;

Figure 3 is a top plan view thereof;

Figure 4 is a bottom plan view of a portion thereof; and

Figure 5 is a section on the line 5—5 of Figure 2 drawn to an enlarged scale.

In the form of the invention here shown there is provided a base or platform 10 supported in any suitable manner as by legs 11. In this platform is an opening or well 12 and at each side of this opening a bearing 13 is mounted on top of the platform.

A shaft 14 is journalled in these bearings and supports, between the bearings, a reel having end flanges 15 formed on a cylindrical body 16 whereon is wound the wire 17.

Just to the rear of the bearings 13 is a second pair of bearings 18 in which are jour-

nalled the pintles 19 of a brake plate 20 extending upwardly and forwardly into braking contact with the peripheries of the flanges 15. This plate is urged into normal braking engagement with said flanges by means of a leaf spring 21. On the forward wall of the well adjacent the bottom thereof is a pair of hinge brackets 22 carrying pivoted leaves 23 to which is fixed the forward edge portion of a brake plate 24 of proper dimensions to pass between the flanges 15. This plate extends in an upward and rearward direction and is pressed into normal braking contact with the outer convolutions of the wire 17 by a leaf spring 25.

To the rear edge of the plate 24 are fixed eyes 26 to which are connected the ends of brake applying strands 27 which are lead rearwardly through openings 28 adjacent the rear edge of the plate 20 and thence upwardly along the rear surface of the plate 20 and forwardly over idler rollers or pulleys 29 mounted revolvably in openings 30 adjacent the free edge of the plate 20.

Extending forwardly from the well 12 are channels 31 and at one forward corner of the body or base is a recess 32 wherein is mounted an operating knob or handle 33 carrying a ratchet 34 wherewith cooperates a pawl 35. Fixed to this handle is a shaft 36 which passes through the channels 31, being provided in these channels with drums 37 whereon are wound the remaining ends of the strands 27. Pins 38 are provided for securing the loose end of the wire 17.

It will be seen from Figure 5 that the strands and plate 24 are at quite an obtuse angle while the strands leading to the drums 37 are substantially at right angles to the plate 20. Consequently, if it be desired to increase the braking effect proper rotation of the winding drums may be caused to wind the strands thereon and this will simultaneously exert braking stress on the brake plates but there will be less stress exerted on the wire brake 24 than on the drum brake 20. Obviously, the pawl and ratchet will maintain such applied stress until the pawl is released from the ratchet.

There has thus been provided a simple and

efficient device of the kind described and for the purpose specified.

It is obvious that changes may be made in the form and construction of the invention without departing from the principles thereof. It is not, therefore, desired to confine the invention to the exact form herein shown and described, but it is desired to include all such as come within the scope claimed.

Having thus described the invention, what is claimed is:

1. The combination with a wire reel; of a reel brake bearing on the reel, a wire brake bearing on the outer convolutions of wire on the reel; and means to apply said brakes simultaneously, said means being arranged to apply the reel brake more forcibly than the wire brake.

2. The combination with a wire reel; of a reel brake bearing on the reel, a wire brake bearing on the outer convolutions of wire on the reel, springs holding said brakes in normal braking positions on said reel and wire, and means to increase the effective application of said brakes simultaneously.

3. The combination with a wire reel; of a reel brake bearing on the reel, a wire brake bearing on the outer convolutions of wire on the reel, springs holding said brakes in normal braking positions on said reel and wire, and means to increase the effective application of said brakes simultaneously, said means being arranged to apply the reel brake more forcibly than the wire brake.

4. In a wire reeling device, a base having a well therein, a pair of bearings at opposite sides of the well, a shaft carried by said bearings, a reel having a body and end flanges on said shaft, said body being arranged to have wire wound thereon, a reel brake plate pivoted rearwardly of the reel and extending forwardly and upwardly and engaging the peripheries, a wire brake pivoted to the forward wall of said well and extending rearwardly and upwardly to bear against the wire on the reel, strands attached to the rear edge of the wire brake and extending in guided relation along the reel brake and forwardly at substantially right angles thereto, said strands being at obtuse angles to the wire brake, and means to exert tension on said strands.

5. In a wire reeling device, a base having a well therein, a pair of bearings at opposite sides of the well, a shaft carried by said bearings, a reel having a body and end flanges on said shaft, said body being arranged to have wire wound thereon, a reel brake plate pivoted rearwardly of the reel and extending forwardly and upwardly and engaging the peripheries, a wire brake pivoted to the forward wall of said well and extending rearwardly and upwardly to bear against the wire on the reel strands attached to the rear edge of the wire brake and extending in

guided relation along the reel brake and forwardly at substantially right angles thereto, said strands being at obtuse angles to the wire brake, springs urging said brakes into normal braking relation with the reel and wire, and means to exert tension on said strands. 70

6. In a wire reeling device, a base having a well therein, a pair of bearings at opposite sides of the well, a shaft carried by said bearings, a reel having a body and end flanges on said shaft, said body being arranged to have wire wound thereon, a reel brake plate pivoted rearwardly of the reel and extending forwardly and upwardly and engaging the peripheries, a wire brake pivoted to the forward wall of said well and extending rearwardly and upwardly to bear against the wire on the reel, strands attached to the rear edge of the wire brake and extending in guided relation along the reel brake and forwardly at substantially right angles thereto, said strands being at obtuse angles to the wire brake, drums on which the remaining ends of said strands are wound, and means to rotate said drums including a pawl and ratchet mechanism to hold the drums against unintentional unwinding. 80

7. In a wire reeling device, a base having a well therein, a pair of bearings at opposite sides of the well, a shaft carried by said bearings, a reel having a body and end flanges on said shaft, said body being arranged to have wire wound thereon, a reel brake plate pivoted rearwardly of the reel and extending forwardly and upwardly and engaging the peripheries, a wire brake pivoted to the forward wall of said well and extending rearwardly and upwardly to bear against the wire on the reel, strands attached to the rear edge of the wire brake and extending in guided relation along the reel brake and forwardly at substantially right angles thereto, said strands being at obtuse angles to the wire brake, springs urging said brakes into normal braking relation with the reel and wire, drums on which the remaining ends of said strands are wound, and means to rotate said drums including a pawl and ratchet mechanism to hold the drums against unintentional unwinding. 90

In testimony whereof I affix my signature.
JOHN BODNAR.
